[57] CLAIM

The ornamental design for a combined clock and calendar, as shown and described.

DESCRIPTION

FIG. 1 is a front elevational view of a combined clock and calendar showing my new design;

FIG. 2 is a right side elevational view thereof, the left side being a mirror image;

FIG. 3 is a bottom plan view thereof, the top plan view being a mirror image thereof; and

FIG. 4 is a rear elevational view thereof.

FIG. 1

FIG. 2

FIG. 3

FIG. 4
